CLAIM

The ornamental design for a cosmetic organizer, as shown and described.

DESCRIPTION

FIG. 1 is a perspective view of a cosmetic organizer showing my new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a left side view thereof; and,

FIG. 7 is a right side view thereof.

The broken lines in the figures are for the purpose of illustrating portions of the cosmetic organizer, which form no part of the claimed design.
